UNITED STATES PATENT OFFICE

ROBERT JOHN NASH, OF BIRMINGHAM, ENGLAND

RACKET FOR GAMES AND THE MANUFACTURE THEREOF

Application filed November 25, 1929, Serial No. 409,491, and in Great Britain February 4, 1929.

It is well known to construct the head or bow of a wooden racket frame by bending one or more strips of ash, or other suitable wood, of appropriate length into a circular, 5 or elliptical shape, and then by reversing the bends in the neck part continuing the ends of the strip in more or less parallel formation to form, or take part in forming, a handle. The frame is usually completed by 10 securing a suitable wedge piece or bridge piece in the throat of the neck of the bow.

In order to avoid some of the stress in the material from which the frame is constructed frames are sometimes constructed 15 with multiple bent strips assembled and glued together along their bent faces. While bending stresses are considerably reduced by this method, it is difficult to ensure glued joints of adequate tenacity, as in practice uniform 20 pressures cannot be obtained between curved surfaces which have been formed by bending; furthermore, the tendency of bent wood to revert to its original form cannot be entirely eliminated, even with the most prolonged seasoning.

This difficulty in gluing curved joints also applies to the fixing of the wedge member used to join the opposite sides of the frame together, and the springing of these joints 30 in use is one of the common causes of failure with tennis and like rackets constructed on this principle.

Furthermore, the necessity for using a piece of high quality timber with parallel 35 grain running lengthwise of the piece of the requisite length to form both the bow of the racket as well as the handle, has a considerable influence on cost.

The objects of the invention are to effect 40 economy in the bendable wood required for the construction; to reduce stress in the neck and shoulders of the frame caused by bending operations, and to improve the nature of the glued joints between the head or bow and 45 the handle portion so that these may be made more durable.

In accordance with the invention the strip or strips of wood forming the head or bow, which will preferably be terminated where 50 the junction with the handle is to be made, are

shaved off at sides of the extremities at inclines so as to present flat faces, and the junction with the handle portion, which is of compound strip form, is made by a succession of overlapping wooden strips all lying 55 on flat surfaces where joints have to be made and all tapering to a feather edge at the parts where any edge is exposed on a joint.

The invention further may consist in removing the front and back surfaces of, and 60 so tapering the extremities of, the head or bow where any inherent strain in those parts due to previous bending operations would operate to produce weakness in the complete frame, and in replacing such portions by 65 straight unbent wood overlapping the tapered down extremities of the bow.

The foundation idea of the invention therefore is the use for the greater part of the shoulders and neck of a racket, where the junction with the handle is made, of unbent 70 wood assembled in pieces so that the grain is directed in the most effective manner to resist the strains and stresses to which the frame is subjected in use, and so that the glued joints between the component pieces 75 will always be made between flat surfaces.

In order that the invention may be thoroughly understood I have appended hereunto drawings illustrating the method of manufacture as applied to one example of a racket frame.

Figure 1, illustrates in front and side elevation a bow frame with wedge which forms 80 the first component.

Figure 2, shows the shoulder overlay in similar views.

Figure 3, similarly illustrates the wedge overlay which is used to form the handle 85 splice.

Figure 4, illustrates in front and side elevation, the wedge overlay shown in Fig. 3, secured to a handle piece.

Figure 5, shows this handle and wedge 90 overlay unit faced off ready for assembling with the other components.

Figure 6, shows the first operation on the component shown in Figure 1.

Figure 7, shows the second operation, 100

where the component shown in Figure 2 is assembled.

Figure 8, shows the third operation, with the second shoulder overlay (Figure 2) glued on to the other side of the frame.

5 Figure 9, shows the fourth operation.

Figure 10, shows the fifth operation.

Figure 11, the sixth.

Figure 12, the seventh.

10 Figure 13, the eighth, and last, operation as far as the invention is concerned.

Figures 14 to 16, show modifications of the bow frame which may be made in the first component.

15 The bow frame *a*, in this example, is made substantially on ordinary lines from a strip of ash of rectangular cross-section bent to the desired shape with a piece of wood *b* glued into the throat and preferably with a U-shaped bent strip *c* inside the bottom of the bow.

20 The bow, instead of being made from a strip long enough to form the handle, is made from a shorter strip terminating at the throat as shown in Figure 1. This bow frame *a* is the first component and in the first operation,

25 Figure 6, it is shaved down on one face over the shoulder, wedge *b* and neck to form a smooth, plane, inclined surface. The second component, Figure 2, comprises a Y-shaped flat shoulder overlay *d*. It may conveniently be made by two parts joined down the centre of the stem of the Y, or as shown in dotted lines.

30 The branches of this Y-shaped overlay are appropriately curved in the fork to conform with the ends of the bow when the stem is in the direction of the handle. Two of these components are employed. In the second operation, Figure 7, this shoulder overlay *d* is glued securely on the inclined surface on the shoulder of the bow frame *a*. The racket frame is then reversed and the other or reverse face of the bow frame together with the inner end of the one shoulder overlay *d* is correspondingly shaved down and on the plane inclined face, so formed, the second shoulder overlay *d* is secured. This is the third operation shown in Figure 8.

35 I next face down the outside of one of the shoulder overlays *d* on the frame *a* so that it terminates in a fine lower edge, Figure 9; and I provide the third component, Figure 3, consisting of a wedge overlay *e* with a tapered upper face *f* corresponding with that machined on the shoulder overlay *d* in Figure

40 9. The wedge overlay *e* is a piece of wood suitable for forming part of the handle; it is preferably about three inches wide and is reversely tapered below the middle portion as at *g* for joining up with the main handle part in a subsequent operation. I secure this wedge overlay *e* on the prepared face of one of the shoulder overlays *d* on the frame *a* forming the fifth operation shown in Figure

65 10.

The next operation, the sixth, Figure 11, comprises the shaving off of the opposite side of the frame *a* with its shoulder overlay *d* to receive the second wedge overlay *e* and handle *h*.

70 The second wedge overlay is made exactly as the first, Figure 3, but before assembly in the racket it is preferably (but not essentially) secured to the handle unit *h* as in Figures 4 and 5. The handle portion *h* is 75 of wood suitable for the main part of the handle and is tapered on one face at one end. The second wedge overlay *e* is secured to the tapered face and the opposite face of the handle is faced to form a smooth even 80 plane with the upper face *f* of the overlay *e*. This handle unit complete with the second wedge is next glued on the inclined face of the racket frame prepared in the sixth operation. This forms the seventh operation 85 shown in Figure 12.

The eighth, and last, operation, as far as the invention is concerned, is the machining of the now completely constructed rough racket frame down ready for the handle slips. 90

95 The shoulders are shaved down on each face of the racket to conform approximately with the plane of the bow frame and the handle sides are tapered, preferably from about the middle of the wedge overlays as shown in Figure 13.

100 The completion of the handle by the usual fillets or slips to give the desired shape, and the shaping of the exterior of the throat and frame and the finishing of the latter may follow on any suitable lines according to the ultimate finish and form required.

105 It may be desirable to avoid the reverse bending of the ends of the bow frame *a*, even when this is made from a short strip only and shaved down to obviate the bad effects of the bending in the jointing processes. I have shown in Figure 14 and 16 alternative forms of bow frame constructions suitable for forming the first component or "blank" 110 for the subsequent operations.

115 In Figure 14 the ends of the frame are brought face to face and the bottom angle of the frame is approximately a right angle in which a triangular wedge *b* is fitted.

120 In Figure 15, there is no reverse bending of the frame strip but the ends are shaped to complete the oval. No wedge is inserted but two U reinforcing strips *c* and *i* are employed.

125 In Figure 16 an ordinary bend of frame is employed but the wedge has an integral curved reinforcing piece on the inside so that parts *b* and *c* of Figure 1 are combined.

130 These modifications would necessitate slight modifications in the shape of the overlying parts which are to finish the frame and build up the handle, but the structure and method of manufacture is unaltered.

I claim:—

1. An improved racket for games in which the faces of the lower part of the bow frame are each shaved off at an inclination to leave a flat inclined face terminating at or near the throat, and the junction with the handle is made by a double inclined overlay member secured to the frame and to the handle, all the joints being made on flat faces all of which taper to feather edges where an edge is exposed at a joint.
2. An improved racket for games comprising in combination a bow frame to carry the interlaced striking face, which bow frame has its shoulder part, where the junction with the handle is made, shaved down to form an incline on each face terminating at or near the throat, a separately formed handle portion, a pair of shoulder overlay members for overlying and securing on the inclined faces of the shoulder, a pair of doubly inclined wedge overlay members one face of each of which is secured on a shoulder overlay and the other inclined face of which is secured on an inclined face on a handle piece.
3. An improved racket for games comprising in combination a bow frame with a wedge piece between the extremities, said frame being shaved down on each face, including said wedge piece, to form inclined faces, which terminate at or near the throat of the racket, a pair of Y-shaped overlay members secured upon the said inclined faces, said overlay members being shaved down to form inclined faces upon which the upper inclined faces of a pair of double inclined or wedge overlay members are secured, and a separately formed handle member to which the lower inclined faces of the wedge overlays are secured.
4. An improved racket frame comprising in combination a suitable bow frame the faces of the lower part of which are shaved off to form even inclined plane surfaces which terminate at the throat of the racket, a shoulder overlays secured on said surfaces and tapered off to feather edges at their ends, double wedge overlays secured thereon and on inclined faces of a handle member.
5. An improved racket comprising in combination, a bow frame to carry the usual interlaced striking face and a handle; tapered faces on the shoulder part at the bottom of said frame which frame terminates at the throat of the racket, shoulder overlays secured thereon, said overlays being of approximately Y-shape and being comprised of two components secured together with the grain oppositely disposed, doubly inclined wedge overlays secured on prepared inclined faces on the outsides of said shoulder overlays, said wedge overlays having inclined faces for joining on smooth inclined faces on said handle.

In testimony whereof I affix my signature.
ROBERT JOHN NASH.
